Des. 177,098
Patented Mar. 13, 1956

177,098

CRAWLER TRACTOR OR SIMILAR ARTICLE

Charles M. Jordan, Birmingham, Mich., assignor to General Motors Corporation, Detroit, Mich., a corporation of Delaware

Application August 3, 1955, Serial No. 37,303

Term of patent 7 years

(Cl. D14—3)

Fig. 1

Fig. 2

Fig. 3

Fig. 4

Fig. 1 is a side elevational view of a crawler tractor or similar article embodying my new design;

Fig. 2 is a top plan view of the design shown in Fig. 1;

Fig. 3 is a rear elevational view of the design shown in Fig. 1; and

Fig. 4 is a front elevational view of the design shown in Fig. 1.

The dominant features of my design reside in the full line portion of the drawings.

I claim:

The ornamental design for a crawler tractor or similar article, substantially as shown and described.
